United States Patent Office

Des. 180,908
Patented Sept. 3, 1957

180,908

CAN OPENER

Michael J. LaForte, Park Ridge, Ill., assignor to Vaughan
Mfg. Co., Chicago, Ill., a corporation of Illinois

Application January 16, 1957, Serial No. 44,510

Term of patent 14 years

(Cl. D22—2)

Fig. 1.

Fig. 2.

Fig. 3.

Fig. 4.

Fig. 5.

Fig. 6.

Fig. 1 is a side elevation of a can opener embodying my design;

Fig. 2 is an elevation of the opposite side of the opener;

Fig. 3 is a top plan view;

Fig. 4 is a bottom plan view;

Fig. 5 is an end elevation viewing the opener of Fig. 1 from the right hand side thereof; and

Fig. 6 is an end elevation of the opener opposite to Fig. 5.

I claim:

The ornamental design for a can opener, substantially as shown.
